AWNING

Carl J. Olson, Atlanta, Walton E. Bobo, Decatur,
and Forrest H. Hudson, Tucker, Ga.

Application April 15, 1952, Serial No. 19,332

Term of patent 14 years

(Cl. D21—6)

To all whom it may concern:

Be it known that we, Carl J. Olson, Walton E. Bobo and Forrest H. Hudson, all citizens of the United States of America, residing respectively at Atlanta, in the county of De Kalb and State of Georgia, at Decatur, in the county of De Kalb and State of Georgia, and at Tucker, in the county of De Kalb and State of Georgia, have invented a new, original, and ornamental Design for Awning, of which the following is a specification, reference being had to the accompanying drawing, forming part thereof, and wherein:

Fig. 1 is an orthographic view of an awning, showing our new design;

Fig. 2 is a front elevational view thereof, on a slightly reduced scale;

Fig. 3 is a side elevational view thereof, on a slightly reduced scale; and

Fig. 4 is a bottom plan view thereof, on a slightly reduced scale.

The side of the awning not shown has substantially the same appearance as the side shown in Fig. 3.

We claim:

The ornamental design for an awning, substantially as shown and described.

CARL J. OLSON.

WALTON E. BOBO.

FORREST H. HUDSON.
